UNITED STATES PATENT OFFICE.

JOHN SOKOLOWSKI, OF MILWAUKEE, WISCONSIN, ASSIGNOR OF ONE-HALF TO LUDWIK PIECHOCKI, OF MILWAUKEE, WISCONSIN.

BAYONET AND GUN-SOCKET THEREFOR.

1,317,051.

Specification of Letters Patent. Patented Sept. 23, 1919.

Application filed June 16, 1919. Serial No. 304,533.

To all whom it may concern:

Be it known that I, JOHN SOKOLOWSKI, a citizen of Poland, residing at Milwaukee, in the county of Milwaukee and State of 5 Wisconsin, have invented certain new and useful Improvements in Bayonet and Gun-Sockets Therefor, of which the following is a specification.

The primary object of the present invention is to provide a bayonet attachment for guns wherein the bayonet is normally carried within a housing formed at the muzzle end of the gun barrel with automatic means for projecting and limiting the outward 10 movement of the bayonet to its operative position when it is desired to use the gun during a charge.

Another object of the invention is to provide a gun having a bayonet normally housed therein and wherein the bayonet, when certain retaining devices are released, is permitted during a fencing operation automatically to move forward to the limit 15 of its movement and be rigidly supported in its full operative position.

With the above and other objects in view, the invention consists in the combination and arrangement of parts herein fully described in connection with the accompanying drawing, in which like reference characters indicate similar parts throughout the several views.

In the drawing,

Figure 1 is a side elevational view of the 20 muzzle end of a gun constructed in accordance with the present invention with a portion of the muzzle end thereof broken away and with a bayonet in operative position therein,

Fig. 2 is a view similar to Fig. 1 with the bayonet in retracted position and with the bayonet housing shown in section,

Fig. 3 is a bottom plan view of the construction shown in Fig. 1,

Fig. 4 is a cross sectional view taken on line IV-IV of Fig. 3 showing the retaining shoe in the bayonet housing for engaging the bayonet while in projected position,

Fig. 5 is a cross sectional view taken on line V-V of Fig. 4,

Fig. 6 is a sectional view of a portion of

the gun barrel and bayonet casing showing the bayonet projecting spring and the closure plug for the bayonet casing and

55

Fig. 7 is a cross sectional view taken on line VII-VII of Fig. 4.

Referring more in detail to the accompanying drawing, there is illustrated the muzzle end of a gun barrel 8 having a bayonet housing or casing 9 preferably formed integral therewith, the bayonet casing terminating at the extreme muzzle end of the barrel and being of a length to completely house the bayonet 10.

60

The interior of the bayonet casing 9 is rectangular in cross section and the stock 11 of the bayonet is of similar formation and relatively long so that the bayonet will slide within the casing and be prevented from relative rotary movement and retained centrally positioned at all times. The inner open end of the bayonet housing is closed by a screw plug 12 having secured to the inner face thereof an expansion coil spring 13 that is engaged and compressed by the stock 11 of the bayonet 10 when the bayonet is in its completely retracted position as shown in Fig. 2.

65

With the bayonet positioned in the housing 9, the same is engaged at the pointed end 14 thereof by a shoe 15, the inner end of the shoe 15 being provided with a recess 16 into which the pointed end of the bayonet is received and protected thereby. The shoe

70

15 is positioned in the enlarged outer end 17 of the bayonet casing 9 and is carried by a pair of pins 18 that freely project through openings provided in the adjacent wall of the outer end 17 with expansion coil springs 19 surrounding the rods between the shoe 15 and wall of said casing 17. An operating handle 20 freely projects through the wall of the casing 17 and has threaded engagement with the shoe 15 and is surrounded between said shoe and casing wall by a similar spring 19.

75

The springs have a normal tendency to force the shoe inwardly into the path of movement of the bayonet 10 and when the shoe is moved toward the wall of the casing 17 to permit the spring 13 to assist the outwardly sliding movement of the bayonet, pulling pressure upon the handle 20 is released and the

80

85

90

95

100

shoe will ride upon the outwardly moving bayonet until the socket portion 21 in the bayonet moves into registration with the shoe 15 at which time the shoe will enter 5 the socket 21 and retain the bayonet rigidly positioned and ready for use.

From the above detailed description of the invention, it is thought that the construction and operation thereof will at once 10 be apparent, it being noted that the bayonet 10 is retained in the casing 9 against the tension of the coil spring 13, by the spring pressed shoe 15 having the inner socketed end 16 engaging the pointed end 14 of the 15 bayonet. When it is desired to have the bayonet 10 operatively positioned relative to the muzzle 8, it is only necessary to laterally shift the shoe 15 in the enlarged housing section 17 by pulling upon the handle 20 20 which will free the outer end of the bayonet from the shoe socket and by the expansion of the spring 31 assisted by a throwing or charging movement of the gun, the bayonet will be thrown forwardly with the shoe riding thereover until such time as the shoe registers with the socket in the bayonet stock 11 whereupon the springs 19 will exert their force to move the shoe into said socket and rigidly position the bayonet in operative position 25 for immediate use. The bayonet is replaced in the casing 9 for removing the shoe from the socket 21 and compressing the bayonet against the tension of the spring 13, one of the main functions of the spring 13 30 being to provide a cushion seat for said bayonet and further to protect the point 14 thereof, the spring 13 and shoe 15 coöperating to hold the bayonet in the casing against any possible relative movement.

40 While I have herein shown and described the preferred embodiments of my invention, it is nevertheless to be understood that minor changes may be made in the form, combination and arrangement of parts without deviation from the spirit and scope of the invention as claimed.

45

What I claim as new is:—

1. In combination with a gun barrel, a bayonet slidably supported thereby and means for limiting the outwardly sliding movement of said bayonet, said means moving transversely of said gun barrel for engagement with the forward end of said bayonet when in inoperative position.

2. In combination with a gun barrel, a bayonet slidably supported thereby, means for limiting the outwardly sliding movement of said bayonet, said means moving transversely of said gun barrel for engagement with the forward end of said bayonet when in inoperative position, and resilient means associated with the first named means for holding the same in operative position.

3. A device of the class described comprising a gun barrel, a housing carried thereby, a bayonet slidably mounted within said housing, and having a socket in the side thereof adjacent its inner end, a tensioned shoe adapted to move transversely of the outer end of said socket and normally in engagement with the outer end of said bayonet, the said shoe adapted to be received in the bayonet socket when the bayonet is projected from said casing.

4. A device of the class described comprising a gun barrel, a housing carried thereby, a bayonet slidably mounted within said housing and having a socket adjacent its inner end, a shoe adapted to be moved transversely of the outer end of the casing, rods carried by said shoe freely extending through the casing wall, an operating handle for said shoe secured thereto and extending through said casing wall, and expansion coil springs surrounding said rods and handle, the shoe adapted to be received in said bayonet socket when said bayonet is projected from said casing and to limit the outward sliding movement of said bayonet.

In testimony whereof I affix my signature. 90

JOHN SOKOLOWSKI.
